CLAIM

I claim the ornamental design for a pillow support, as shown and described.

DESCRIPTION

FIG. 1 is a top perspective of a pillow support of my new design.

FIG. 2 is a bottom perspective of the pillow support.

FIG. 3 is a right-side view of the pillow support.

FIG. 4 is a left-side view of the pillow support.

FIG. 5 is a front view of the pillow support.

FIG. 6 is a rear view of the pillow support.

FIG. 7 is a top view of the pillow support; and,

FIG. 8 is a bottom view of the pillow support.

1 Claim, 8 Drawing Sheets
